UNITED STATES PATENT OFFICE.

NORMAN C. RENDLEMAN, OF DORMONT, PENNSYLVANIA, ASSIGNOR, BY MESNE ASSIGNMENTS, TO JONES & LAUGELIN STEEL CORPORATION, OF PITTSBURGH, PENNSYLVANIA, A CORPORATION OF PENNSYLVANIA.

PROCESS OF MAKING METALLIC STRUCTURAL ELEMENTS.

Application filed February 13, 1922. Serial No. 536,383.

To all whom it may concern:

Be it known that I, NORMAN C. RENDLEMAN, a citizen of the United States, and a resident of Dormont, county of Allegheny, State of Pennsylvania, have invented an Improvement in Processes of Making Metallic Structural Elements, of which the following is a specification.

The present invention relates to the manufacture of metallic beams and like structural elements intended to resist heavy strains, and which are commonly rolled steel shapes such as I-beams, T-beams, etc. It is also applicable to flat strips and plates.

It has been proposed heretofore to increase the strength of such beams per unit of weight, particularly in resistance to transverse bending and compressive strains, by giving to the integral web portion a truss structure such as is common in non-integral built-up beams. Taking a finished I-beam as an example, it has been proposed to cut the web by two or more series of longitudinal slits in staggered relation to one another, and then after the beam has been suitably heated, to separate the opposite side flanges, thus stretching the metal in the web and opening out the slits, so as to form integral diagonal truss-members connecting the opposite flanges, and resolving the web as a whole into a series of adjacent oppositely arranged triangles without changing the lineal dimensions of the beam.

An object of my invention is to manufacture the same product by a method which does away with the stretching of the metal of this truss-member. In this operation the web is slitted and the beam heated as before. It is then passed through rolls which operate only upon the web of the beam, and which reduce and elongate the metal of the web, while the opposite flanges remain of the same length, such elongation of the web causing it to take the form of undulations, and by separating the flanges the beam is spread or expanded to finished form and width without stretching the metal.

Another object of my invention is to improve upon prior methods by expanding the beam immediately as it comes from the finishing-pass of the beam-mill, and without reheating, thus greatly reducing the cost of manufacture and at the same time obtaining a more uniform and homogeneous product.

A further object is to so control the undulations of the web, caused by its reduction and elongation in the second method, as to reduce strains to a minimum. A still further object is to give to the truss-members of the finished beam a cross-sectional form of maximum strength.

In the accompanying drawings there is illustrated the practice of the invention in connection with an I-beam. Figure 1 shows in elevation and in cross-section a slotted I-beam; Figure 2 is a longitudinal section of the same after the reduction and elongation of the web by rolling; Figure 3 shows in perspective the preferred manner of separating the opposite flanges and thereby forming the truss-members from the web; Figure 4 is a view in elevation of the finished beam; Figures 5 and 6 are enlarged cross-sectional views on the lines V—V and VI—VI, respectively of Figure 4.

The entire operation is performed upon the beam or other shape as it comes from the finishing pass of the rolling-mill, and without reheating. This results in great economy, and gives a better product since the metal is not subjected to deterioration by repeated heating. The beam as rolled is first subjected to the action of a shear, which forms in the web the slits 1 as shown in Figure 1, the adjacent rows of slits being in staggered relation to one another. In the present case three rows of slits are shown, but there may be only two rows, one row adjacent to each of the flanges, or in other cases there may be more than three rows.

From the shear the beam is passed through a rolling-mill, the rolls of which operate only upon the web, leaving the opposite flanges free, and the effect of this rolling is to reduce and elongate the web of the beam without changing the length of the opposite flanges. This operation will cause longitudinal bows or undulations between the points 2 where the web remains tied to the flanges, and in order to control these undulations, guides 3 are placed above and below the web portion of the beam at the discharge side of the roll pass, thus giving the web portion of the beam the general form shown in Figure 2.

The spreading apart of the opposite flanges may be accomplished in many ways, as may be preferred, or dependent upon the

particular shape of the beam or other section being operated upon. In the case of the I-beams it is preferred to accomplish this stretching by passing the rolled section 5 longitudinally over gradually diverging guides 5 as shown in Figure 3, thus bringing the article to the finished width. Then if found necessary or desirable it may be subjected to another rolling operation, though 10 that may not always be necessary.

The pass between the rolls may of course be a plain pass, which will result in the truss-members having a general rectangular form in cross-section. But in order to make 15 the truss-members of such cross-sectional form as to give them maximum strength, it is preferred to form the roll pass so as to impart to the metal of the web between each row of slits the form shown in Figure 20 5 of the drawings, which is essentially the form of an I-beam, and when the flanges are pulled apart the truss-members will consequently have this cross-sectional form. Their form at the points of their junction 25 with each other is shown in Figure 6.

It will be apparent that the method which constitutes the present invention may be practiced upon beams and like articles of a variety of shapes, and it may also be used 30 for the formation of a truss structure or network between the opposite margins of flat plates. Such flat reticulated plates may be used to great advantage in the construction 35 of roadways, and they have other valuable uses as well. For that reason in the appended claims the term "metal bar" is used generally to designate indifferently beams, plates or other metallic shapes upon which the method may be used.

40 It is also apparent that the method is capable of being practiced by the use of varieties of apparatus, and that it is also capable of a considerable amount of modification without departure from the essence 45 of the invention.

Without limiting myself to the embodiments described, I claim the following as my invention:

1. The method of fabricating a metallic 50 bar, which comprises slitting the metal of the bar between opposite marginal portions, rolling said slit portion to reduce its cross-sectional area and elongate it with reference 55 to said marginal portion, and spreading the bar by separating said marginal portions without substantial elongation of said slit portions.

2. The method of fabricating a metallic 60 bar which comprises slitting the median portion to form two parallel rows of connecting

members joined to each other at adjacent ends and to the margins of the bar at opposite ends, rolling said connecting members to substantially finished cross-sectional shape, and separating the margins of the bar 65 to open out said connecting members to form an open web structure connecting said margins.

3. The method of fabricating a metallic bar, which comprises rolling the bar, and 70 while it is still at the elevated temperature incident to such rolling, slitting the metal of the bar between opposite marginal portions, reducing and thereby elongating said slit portions, and spreading the bar by separating 75 said marginal portions.

4. The method of fabricating a metallic bar, which comprises rolling the bar, and while it is still at the elevated temperature 80 incident to such rolling, slitting and rolling to greater length the metal of the bar between its opposite longitudinal marginal portions and without extending said marginal portions, and then spreading the bar.

5. The method of fabricating a metallic 85 bar, which comprises slitting and rolling to greater length the metal of the bar between its opposite longitudinal portions without extending said marginal portions, thereby giving said rolled portion an undulatory 90 form, controlling the amplitude of the undulations and spreading the bar.

6. The method of manufacture of trussed metallic beams, which comprises rolling the beam, forming in its web a plurality of rows 95 of longitudinal slits, the slits in adjacent rows being in staggered relation, reducing and elongating the slitted web while hot and without extending the opposite margins of the beam, and in such rolling giving to the 100 metal between adjacent rows of slits a beam-like cross-sectional form, and then spreading apart said margins of the beam and thereby laterally opening the slits, substantially as described.

7. The method of fabricating a metallic bar which comprises slitting the median portion to form two parallel rows of connecting members joined to each other at adjacent ends and to the margins of the bar at opposite ends, rolling said connecting members to reduce and lengthen them, and separating the margins of the bar to open out 110 said connecting members to form a lattice connecting said margins.

In testimony whereof, I have signed my name to this specification this 11th day of February, A. D. 1922.

NORMAN C. RENDLEMAN.
